ZURICH, SWITZERLAND.

DEVICE FOR BALANCING SHAFTS.

1,296,180.

Specification of Letters Patent.

Patented Mar. 4, 1919.

Application filed July 9, 1918. Serial No. 244,105.

To all whom it may concern:

Be it known that I, BENJAMIN GRAEMIGER, a citizen of the Republic of Switzerland, residing at Zurich, Hardturmstrasse 19, 5 Switzerland, have invented certain new and useful Improvements in Devices for Balancing Shafts; and I do hereby declare the following to be a clear, full, and exact description of the invention, such as will enable 10 others skilled in the art to which it appertains to make and use the same, reference being had to the accompanying drawing, and to letters or figures of reference marked thereon, which form a part of this specification. 15

The invention relates to a device for the axial balancing of the shaft of turbo-blowers and compressors, turbo-pumps, turbines or other similar machines by means of an 20 impeller of an auxiliary centrifugal pump fitted on the shaft to be balanced and supplying a balancing fluid.

According to the invention the impeller of such auxiliary pump is designed to act as a 25 balancing disk which forms with the auxiliary pump casing a pressure chamber connected to two ring clearances, one of which remains constant and the other varies when the shaft is axially displaced.

A balancing device already known is the one the characteristic feature of which is the fitting of the impeller of an auxiliary pump on the shaft of a blower or compressor so that the axial thrust produced by the 35 pump counteracts the thrust produced by the blower or compressor. In order to regulate the action of the auxiliary pump and adjust its thrust to that of the blower or compressor, a spring loaded throttle valve 40 is fitted on the pressure piping of the auxiliary pump. This valve is not accessible during the running of the set, for which reason it must be adjusted to a given over-pressure before starting. This entails the 45 repeated stopping and starting of the set until the thrust is approximately balanced. This device offers no certainty that the desired balance has been attained or that the thrust of the blower is exceeded or otherwise 50 and to what extent. Furthermore, the regulation is dependent on the condition of the oil, its temperature and its degree of fluidity.

In contradistinction to the above described device, the one forming the object of the 55 present invention works automatically and in a thoroughly reliable manner. The use of independent movable valves is completely avoided. The auxiliary pump does not occupy much more room than the above described contrivance and forms a self contained balancing device.

The annexed drawing shows an embodiment of the invention in connection with a two stage rotary blower. The air enters 65 into the blower, through the branch 1, and exhausts through the branch 2. Both runner wheels 3 and 4 are subject to axial thrust, exerted by the air, from right to left. To balance the thrust an auxiliary centrifugal 70 pump is fitted on the high pressure side, chiefly for the purpose of delivering oil for the balancing of the shaft, but also for the lubrication of the bearings and for the operation of the regulating devices if desired. 75 The oil can be made to circulate in one or two separate cycles. In the latter case, the "inner" cycle is the one inside the pump which acts as a balancing device, while the "outer" one is the one outside the pump, 80 which leads the oil to another point where it is used, for instance, to the bearings and from the latter back to the pump. The impeller of the auxiliary pump 8 is provided with blades 9 and is fixed to the shaft 5 85 which runs in the bearings 6 and 7. Oil is supplied to these runner blades through the suction chamber 10. After leaving the runner blades 9 the oil flows under pressure along two separate paths. One portion reaches the cylindrical ring clearance 11 and from same flows into the ring chamber 12. The latter is the pressure chamber which is limited on one side by the clearance 11 which remains constant when the shaft is axially 90 displaced and on the other side by the clearance 13 which varies when the shaft is axially displaced. On the right of runner wheel 8, i. e. in the chamber 14 the pressure is about equal to that in the suction chamber 10. The oil which reaches the chamber 14 from the pressure chamber 12 by passing through the variable clearance 13, flows through the channel 14^a back to the suction chamber 10 95 and begins its cycle over again. 100 The other portion of the oil which leaves 105

The other portion of the oil which leaves

the runner wheel 9 flows through the diffuser 15 into the pressure chamber 16 and from same through the branch 17 and through the pipe 18 connected to same and leading to a spot outside the pump, where it is to be used, *i. e.* to the bearings 6 and 7, from which it returns through the pipes 19 and branch 20 to the suction chamber 10 of the pump. In this manner the outer cycle is closed.

- 10 The runner wheel 8 of the auxiliary pump is subject to a side thrust from the left to the right, owing to the overpressure of the oil in the side chambers 21 and 12. The pressure in chamber 21 varies very little during the running of the pump. On the contrary, the pressure in the chamber 12 varies considerably, because the section of its outlet 13 varies also considerably owing to the axial displacement of the shaft. When the 15 blower is running under constant pressure, the shaft 5 automatically takes up such a position that the pressure which is produced in the ring chambers 21 and 12, exerts on the runner wheel 8 a side thrust from the left to the right which balances the side thrust acting upon the runner wheels 3 and 4.
- 20 As shown on the drawing, the whole balancing device is simple and perfectly safe in working. For the purpose of better illustrating the invention the pump, in proportion to the blower, has been designed on a 25 larger scale. In actual practice, however, the pump would occupy considerably less room.

- 30 Balancing disks working with a constant and with a variable clearance, are already known but the required oil pressure is produced by a pump arranged outside of the machine. The advantage of the invention 35 consists in the compactness of the auxiliary pump and balancing disk, whereby space and manufacturing costs are reduced. In addition to this, the machines are more easy to watch and are safer in working.

40 45 What I claim is:

1. In a device for the axial balancing of the shaft of turbo-blowers or compressors, turbo-pumps, turbines or other similar machines, in combination: an auxiliary centrifugal pump, the impeller of which is fitted on the shaft to be balanced, a pressure chamber formed by the auxiliary pump casing with this impeller which acts as a balancing disk, two ring clearances connected with said pressure chamber, one of these clearances remaining constant and the other varying when the shaft is axially displaced, a chamber formed in the pump casing behind the impeller, said chamber being connected with the pressure chamber by means of the variable clearance, a connection between the chamber behind the impeller and a suction chamber before the impeller, substantially as set forth.

varying when the shaft is axially displaced, substantially as set forth.

2. In a device for the axial balancing of the shaft of turbo-blowers or compressors, 60 turbo-pumps, turbines or other similar machines, in combination: an auxiliary centrifugal pump, the impeller of which is fitted on the shaft to be balanced, a pressure chamber formed by the auxiliary pump casing with this impeller, a ring clearance connecting the outlet of the impeller blades with the pressure chamber, said clearance being cylindrical and concentric with the axis of the pump, and another ring clearance connected to the pressure chamber, said ring clearance being perpendicular to the axis of the pump, substantially as set forth.

3. In a device for the axial balancing of the shaft of turbo-blowers or compressors, 75 turbo-pumps, turbines or other similar machines, in combination: an auxiliary centrifugal pump, the impeller of which is fitted on the shaft to be balanced, a pressure chamber formed by the auxiliary pump casing with the impeller, said chamber being connected with the outlet of the impeller blades through a cylindrical clearance concentric with the axis of the pump, a second clearance perpendicular to the axis of the 85 pump connecting the pressure chamber with a chamber formed in the pump casing behind the impeller, said chamber being connected with a suction chamber before the impeller, substantially as set forth.

4. In a device for the axial balancing of the shaft of turbo-blowers or compressors, 90 turbo-pumps, turbines or other similar machines, in combination: an auxiliary centrifugal pump, the impeller of which is 95 fitted on the shaft to be balanced, a pressure chamber formed by the auxiliary pump casing with the impeller which acts as a balancing disk, two ring clearances connected with said pressure chamber, one of these clearances remaining constant and the other varying when the shaft is axially displaced, a chamber formed in the pump casing behind the impeller, said chamber being connected with the pressure chamber by means of the 100 variable clearance, a connection between the chamber behind the impeller and a suction chamber before the impeller, substantially as set forth.

In testimony that I claim the foregoing as 110 my invention, I have signed my name.

BENJAMIN GRAEMIGER.
